SIMULATED SOUNDING SPACE WEAPON TOY
Amedee James Valentine, North Hollywood, Calif., assignor of twenty-five percent to Ronald Stein, and twenty-five percent to Sanford Astor, both of Northridge, Calif.

Filed July 9, 1965, Ser. No. 470,671
5 Claims. (Cl. 46—227)

ABSTRACT OF THE DISCLOSURE

This invention comprises a sound producing child's toy in the shape of a space weapon or a space ship. It is battery operated and by means of an external switch depressed by the child a note of fixed frequency is impressed upon a transistor. Rotation of a knob by the child controls a potentiometer which changes the pitch of the sound produced. Manipulation of the switch and knob allows variation in the sound produced by the toy.

This invention relates generally to a child's toy and more particularly to a child's toy which when activated by the child produces a sound which may be varied by manipulation of the toy.

Many toys which make noise have been marketed for children. These toys are mainly of the percussive type in which a sharp sound is produced by striking a portion of the toy or by two parts of the toy which strike automatically together. Toys of this type are irritating to parents or any other persons in the vicinity. In addition these toys tend to make children more excited, nervous, and hard to control.

The toy of the present invention when actuated by the child produces a steady pitch or sound more harmonious and soothing than the toys previously made for children. A need has long existed for a child's toy which would soothe a child rather than excite him. A tone or sound which to some extent imitates a human voice can provide long hours of quiet pleasure for a child and his parents. While talking dolls have been made, the child must operate them by pulling a cord, an action of which any child quickly tires.

The toy of the present invention does not imitate words, however it does allow the child to constantly vary a pitch or sound, turn it off and on, so that the child has control over the sound created. Since the toy is battery operated no effort need be exerted by the child.

These and other advantages of the present invention will be more fully set forth in the following specification and claims, considered with the attached drawing in which:

FIG. 1 is a circuit diagram;

FIG. 2 is a side elevation of an embodiment of the present invention;

FIG. 3 is a perspective view of the embodiment shown in FIG. 2;

FIG. 4 is a perspective view of a portion of the bottom of the embodiment shown in FIG. 5 and

FIG. 5 is a perspective view of another embodiment of the present invention.

Referring now to FIG. 1, there is shown a battery 10 connected to a transistor 12. The battery is connected to the transistor emitter 14. The transistor base 16 is connected through a potentiometer 18 to one side 20 of a transformer 22. The transistor collector 24 is connected to the other side 26 of the transformer 22, as is a speaker 30 and if desired a lamp (not shown). The lamp is not required of course to produce the sound but may be employed to flash when the circuit is closed, if desired. A

2

switch 34 is provided in the circuit connected to battery 10. A condenser 28 is connected between the transformer 22 and the transistor base 16 to form the circuit.

When the switch 34 is closed a note of fixed frequency is impressed upon the transistor 12 which note can be audibly heard through the speaker 30. When the potentiometer 18, the variable resistance, is adjusted, the frequency of the note is altered and a different pitch is heard through speaker 30.

Referring now to FIG. 2 and FIG. 3, the toy of the present invention is shown. The body of the toy 36 is in the shape of a space ship or flying saucer; that is the body 36 consists of a lower conical section 38. An upper conical section 40 is inverted on top of section 38 so that the larger diameter of the two conical sections meet and are fixedly attached together at the center seam 42. The body may be made from any solid material such as aluminum or plastic. A clear plastic is particularly desirable since the child then has an opportunity to view the electrical components which would be fixedly attached to the inner surface of the body 36.

The cannon or weapon 44 of the space ship is in the form of a button fixedly attached through the body 36 at a point just below the middle seam 42 of the body 36. Depressing button 44 actuates switch 34 located inside body 36. Depressing button 44 therefore closes the circuit shown in FIG. 1 and a note of fixed frequency and pitch is heard through speaker 30.

The power generation unit 46 of the space ship in the shape of a conical dial is fixedly attached to a rod (not shown) passing through the top of the upper portion 40. Rotation of the power generation unit 46 modifies the resistance of the potentiometer 18 of the circuit shown in FIG. 1, changing the pitch and frequency of the note heard.

Manipulation of the button 44 on the one hand and the dial 46 on the other hand allows the child to produce a constant sound of fixed frequency, to produce a constant sound of varying frequency or an intermittent sound of constant or varying frequency.

A color code 48 may be provided if desired, fixed to upper portion 40 around dial 46. A viewing slot 50 is provided in the power generation unit, dial 46, so that rotation of the dial 46 rotates the slot 50. Any given frequency or setting of the potentiometer 18 by setting dial 56 will correspond to a color seen in the viewing slot 50.

FIG. 4 shows the bottom 52 of the space ship body 36 with vents 54. The speaker 30 shown in FIG. 1 is fixed inside and adjacent the bottom 52 so that the sound can be heard through vents 54.

FIG. 5 shows an alternative child's toy, a space weapon or gun, in the form of an elongated cone 56. A smaller cone 58 is inverted at the upper end of cone 56 so that the smaller diameter of each cone 56 and 58 are joined at seam 60. A trigger device 62, in the form of a button is fixedly attached through the cone 56. Depression of button 62 closes the circuit shown in FIG. 1, to produce a constant sound of fixed frequency and pitch. A power control knob 64, designated to control the amount of power in the space weapon, is rotated to vary the resistance, adjust the potentiometer 18 mounted inside the weapon, and varies the frequency and pitch of the note heard through speaker 30. As in the space ship toy of FIGS. 2 and 3, a child can manipulate the switch and knob to create a constant or varying tone. A color code 66 viewed through slot 68 allows repetitive setting of the knob at any certain pitch.

Lamp 32 is optional and can be included in either the design of FIGS. 2 and 3 or FIG. 5 in addition to the sound created and is preferably viewed through a transparent section.

Children playing with the toy of this invention develop coordinative and rhythmic ability in both their hands through manipulation of the switch and knob. In addition the sound quality tends to soothe the children and keep them relaxed and quiet.

It is evident that changes and modifications may be made in the embodiments of the invention described above without departing from the spirit of the invention. However, the embodiments shown are preferred due to their portability, their relationship to present interest in space exploration, particularly to children, as well as the fact that their shapes provide a convenient receptacle for the components and they allow the child to operate the toy easily while coordinating two hands.

I claim:

1. A child's toy in which a sound is produced comprising a toy space weapon having circuit means including sound producing means, movable switch means simulating a trigger device and potentiometer control means including a revolvable knob simulating a power unit wherein depression of said trigger device closes said circuit causing a sound to be produced and rotation of said power unit changes the pitch of the sound produced.

2. The toy of claim 1 in which depression of said

trigger device causes said switch means to close impressing a note of fixed frequency upon a transistor.

3. The toy of claim 1 in which a light fixed inside said weapon goes on when said trigger device is depressed.

5. The toy of claim 1 in which a color code located on said weapon is visible through a slot in said power unit.

10 4. The toy of claim 1 in which a color code located on said weapon is visible through a slot in said power unit.

5. A child's toy in which a sound is produced comprising a toy space ship having circuit means including sound producing means, movable switch means simulating a weapon and potentiometer control means including a revolvable knob simulating a power unit wherein depression of said weapon closes said circuit causing a sound to be produced and rotation of said power unit changes the

15 pitch of the sound produced.
